DESIGN FOR A GLASS LINER FOR A COM- PORT OR SIMILAR ARTICLE

Clyde S. Whipple, Los Angeles, Calif.

Application February 24, 1937, Serial No. 67,822

Term of patent 14 years

To all whom it may concern:

Be it known that I, Clyde S. Whipple, a citizen of the United States of America, residing at Los Angeles, in the county of Los Angeles and State of California, have invented a new, original, and ornamental Design for a Glass Liner for a Comport or Similar Article, of which the following is the specification, reference being had to the accompanying drawing, forming a part thereof.

Figure 1 is a side elevation of a glass liner for

a comport or similar article, showing my new design.

Figure 2 is a plan view of the article.

Figure 3 is a section taken along line 3—3 of Figure 2.

I claim:

The ornamental design for a glass liner for a comport or similar article, as shown.

CLYDE S. WHIPPLE.
